UNITED STATES PATENT OFFICE

172,143

PHOTOGRAPHIC FILM RACK

George G. Ingham, Amarillo, Tex.

Application August 17, 1953, Serial No. 26,489

Term of patent 14 years

(Cl. D61—1)

To all whom it may concern:

Be it known that I, George G. Ingham, a citizen of the United States of America, residing at city of Amarillo, county of Potter, and State of Texas, have invented a new, original, and ornamental Design for a Photographic Film Rack, of which the following is a specification, reference being had to the accompanying drawing, forming part thereof:

Figure 1 is a perspective view of a photographic film rack, embodying my new design,

Figure 2 is a side edge elevational view thereof, and

Figure 3 is a vertical sectional view, as seen on line 3—3 of Figure 1.

I claim:

The ornamental design for a photographic film rack, as shown.
